UNITED STATES PATENT OFFICE.

MOSES ISAACS, OF NEW YORK, N. Y.

CLOTH-LAYING MACHINE.

1,061,914.

Specification of Letters Patent. Patented May 13, 1913.

Application filed March 13, 1912. Serial No. 683,514.

To all whom it may concern:

Be it known that I, MOSES ISAACS, a citizen of the United States, and a resident of the city of New York, borough of Manhattan, in the county and State of New York, have invented a new and Improved Cloth-Laying Machine, of which the following is a full, clear, and exact description.

My invention is a cloth laying machine and is designed to take cloth, such as woolen cloth that is folded in half, lengthwise, and lay it upon a table in an even pile of layers, for the purpose of cutting it into pieces, to make parts of clothing. The machine is made to take pieces of such cloth which are either in a roll or in folds.

Reference is to be had to the accompanying drawings forming a part of this specification, in which the same characters of reference indicate the same parts in all the views.

Figure 1 is a side elevation of my improved cloth laying machine and table or stand therefor; Fig. 2 is a vertical longitudinal sectional view of my improved cloth laying machine, on the line 2—2 of Fig. 3; Fig. 3 is a top plan view thereof; Fig. 4 is a transverse vertical sectional view taken through the center of the pivot for the cloth supporting frame on the machine; Fig. 5 is a detail view, showing the manner in which the cloth passes over the rollers from the bolt or roll; Fig. 6 is a section on the line 6—6 of Fig. 7; Fig. 7 is a section on the line 7—7 of Fig. 6; Fig. 8 is a top plan view of a portion of the cutter guide; Fig. 9 is a perspective view of one end of the tensioning device carried by my improved cloth laying machine; Fig. 10 is a transverse vertical sectional view of the tensioning device shown on Fig. 9; Fig. 11 is a view of a modification used in connection with my cloth laying machine for the purpose of laying such cloths as are not folded in half lengthwise, into folds of any desired length; Fig. 12 is an end view of the construction shown in Fig. 11; Figs. 13 and 14 are side and end elevations respectively of a measuring device; Fig. 15 is a side elevation of a modified form of cloth laying machine, and Fig. 16 is a view of a detail.

On the drawings, 1 is a stand or table,

along one of the longitudinal edges of which is placed a rail 2. This rail has a projecting rim or edge 3 on its upper side, and is so fixed to the side of the table that the top of this rim will be flush with the table top, but will be separated from the edge of the table by means of a groove 4.

5 is a truck forming a part of my cloth laying machine, this truck having a pair of flanged wheels 6 on one side, which run upon the rim 3 on the rail 2, and a pair of flat wheels 7 on the opposite side, which move upon the smooth surface of the table. Adjacent one end of this truck is arranged a rack 8, which serves to support a bolt or roll of cloth and to let out the same when the cloth is to be laid. This rack is pivoted on a central bolt 8', and carries a pivoted shelf 11, which is attached to supports 9, which are secured to the ends of the shelf 11 adjacent one of the longitudinal edges thereof. Braces 10 are joined at one end to the supports 9, and at the other end to the shelf 11, adjacent the opposite longitudinal edge, to strengthen the same and enable the shelf 11 to bear the weight of the roll of cloth, shown at 13. The end supports 9 are both pivoted at their lower ends to the cloth rack 8, and have projections from their inner faces to be engaged by hooks 9', carried by the sides of the rack, in order that the shelf may be held in upright position.

The rack 8 carries a transverse roller 14 at the top thereof, over which the cloth passes, and this roller has at one end a pinion 15 engaged by a gear 16 having thereon a handle 17. This handle is turned by hand when the car is moved over the surface of the table to rotate the roller 14 and pay out the cloth.

18 and 19 are rollers carried by the rack 8, these rollers being arranged transversely with respect to the truck 5, and the cloth 95 when it is being paid out passes over the same.

The bolt or roll of cloth is partly unwound, and then laid upon the shelf 11 in such position that the loose end will lie at 100 the bottom of the roll, resting directly upon the shelf 11 and extending to the left. This loose end is carried up around the roller 14, then down again under the roll 13, and then

up a second time over the roller 14. It is then passed over the roller 18 and under the roller 19, and out over the end of the truck 5. When the truck 5 moves to the left, the 5 crank 17 is rotated by hand. This causes the roller 14 to revolve, paying out the roll 13. The moment the roll 13 begins to move, the roll 13 will begin to revolve around its longitudinal axis. If the hooks 9' be now 10 released, the roll 13 as it rotates will knock over the shelf 9, causing it to fall into the position shown on Fig. 2. The roll of cloth will then be supported in suspended position and will turn freely as the cloth is paid 15 out, owing to the continued rotation of the roller 14.

At the opposite end of the truck 5 is arranged a plate 20, this plate 20 being of some smooth material and extending transversely of the truck across the terminal edge. Above the plate 20 is a tension device which consists of a bar 21, carrying on its lower surface a facing of suitable cloth, indicated by the numeral 22, side strips 22' 20 being employed to engage the edges of this facing of cloth and hold it in position. The cloth normally passes over the plate 20 and beneath the cloth facing 22 of the tensioning device, as shown on Figs. 1, 2, 3 25 and 10.

At the ends of the tensioning device 21, and adjacent the forward corners thereof, are arranged two pairs of guide blocks 23, each pair of these guide blocks 23 receiving 30 a sliding shoe 24, these sliding shoes being two in number and having pivot pins 25 projecting therefrom, and the ends of these pins being received by apertures in plates 26, carried by the ends of the tensioning device 21. The lower ends of these shoes 24 each have longitudinal slots 27; and 28 are fastening screws passing through the slots 27 in the sliding shoes 24, and engaging the blocks 23 to hold the shoes 24 in adjusted 45 position. By means of this construction the forward edge of the tension device 21 can be raised slightly, as shown on Fig. 10, causing it to engage the cloth adjacent the rear edge of the cloth facing 22. By lowering 50 the tensioning device 21 some in front, a larger width of the cloth facing 22 will come in contact with the cloth, and the result will be that the upper half of the layer of cloth will be stretched as it passes.

55 5' are extensions which project longitudinally from the sides of the truck 5 beyond the end whereon is mounted the tension device 21; and 29 and 30 are transverse guide bars mounted in the extensions 5' at their 60 opposite ends. The bar 30 forms part of a rectangular frame 31, which consists of side members 32 joined at their upper ends to a length of transverse tubing 30', which is mounted upon the bar 30. Two transverse

bars 33 connect the side members 32 of 65 the frame 31 together at the lower part of this frame, and 34 is a quadrant carried by one of the extensions 5' by means of which the frame 31 can be raised or lowered and held in such raised or lowered position, as 70 desired. This quadrant 34 has a curved slot therein which receives a binding nut 35, suitably carried by one of the flat arms 32 of the frame 31, to hold the frame 31 in adjusted position, above the pile of cloth being 75 laid.

36 are bolts having wing-nuts on their outer ends, one of these bolts being carried in the lower end of each of the side arms 32 of the frame 31. The inner ends of these 80 bolts 36 serve as pivot pins for a pair of lateral projections 37, which are made integral with, or secured in any suitable way to, a transverse bar 38, which forms part of the guide which receives the cutter knife 85 for the cloth. This bar 38 has a longitudinal slot 39 therein, extending entirely across the width of the cloth, as shown on Fig. 3, and on the under side of this guide 38 project a series of points 42. These points fit in corresponding holes in a board or plate 40, this board or plate 40 being attached to the under side of the bar 38 by means of springs, shown at 45. This board 40 is slotted to correspond to the slot 39, 95 and the springs 45 hold the board 40 a certain distance away from the under side of the bar 38. Beneath the board 40 and carried at its ends by the side arms 32 of the frame 31, is a third transverse bar 41, this 100 bar having a slot or groove 43 therein, which registers with the slot 39 in the bar 38, and having openings or recesses 44 beneath the openings in the plate or board 40, to receive the points 42. The cloth, as shown 105 in Figs. 6 and 7, passes between the plate 40 and the bar 41, but when the bar 38 and the plate 40 secured to the same are raised by moving the same around their pivot bolts 36, the cloth slides freely over the bar 41. 110 When it is desired to cut the cloth, the bar 38 is forced down until the plate 40 carried beneath the same presses upon the upper surface of the cloth. The bar 38 is now forced down until the points 42 pass through 115 the cloth into the openings 44 in the bar 41. These points hold the cloth securely in position, and to cut the cloth crosswise it is only necessary to insert the blade of a sharp knife 46 into the slot 39 and make a cut 120 from one edge of the cloth to the other. When the guide is swung up, the springs 45 press the plate 40 outward to keep the points 42 from projecting.

46' are standards arranged at the end of 125 the table 1 on each side thereof, and a transverse bar extends across from one standard to the other. On this bar are pivotally

mounted levers 47, carrying at their outer ends a transverse weighted bar 48. This bar 48 rests upon the end of the cloth and holds it down when the truck 5 is moved 5 to the left to lay the cloth. A rod 49 may be used to wrap the end of the cloth around it to afford a more secure engagement for the weighted bar 48.

When the cloth is to be laid, the truck 5 10 of course is adjacent the right end of the table 1, and as it is moved to the left the handle 17 of the gear 16 must be turned to pay out the cloth from the bolt or roll suspended in the cloth rack 8. The outer end 15 of the cloth will be securely held on the table by means of the weighted bar 48, and as the cloth is paid out, the tension device will cause the two layers in which the cloth is folded to be laid smoothly and evenly, 20 with the weft threads arranged straight across the table top. When the required length has been paid out, the bar 38 is forced down to cause the points 42 carried thereby to stick into the cloth between the 25 plate 40 and bar 41, and the length desired is then severed.

Fig. 11 illustrates a way of laying single 30 ply cloth, when such cloth is to be handled. I make use of the truck 5, as before. The cloth is fastened down to the top of the table 1 at its outer end by means of awls 50; and a pair of uprights 51 is secured to the sides of the table adjacent its end. A similar pair of uprights 52 is secured to the 35 sides of the table remote from the uprights 51, and adjacent each of the uprights 52 I place a pair of vertical racks 52'. These racks 52' have a series of notches 53 on their edges adjacent the uprights 52, to receive a 40 bar 54, the said bar being longer than the width of the cloth, so as to reach from the rack 52' on one side to a corresponding rack opposite. The uprights 51 and 52 and the racks 52' will, of course, be spaced far 45 enough apart to allow the frame 31 to pass between them. To lay the cloth, the outer end is fastened to the top of the table by means of the awls 50, and the truck is then moved to the left, paying out the cloth in 50 the usual way. When it has passed to such a distance that the end of the frame 31 clears the uprights 52, it is stopped, and one of the bars 54 is laid across the layer of cloth, the ends of this bar lying between 55 the uprights 52 and the racks 52', and resting in one of the notches 53 carried on the racks 52'. The truck is then moved back until the bars 33 are past the uprights 51, and a similar rod 54 is then laid across the 60 second fold of cloth, so that it will prevent this layer from being pulled back with the truck when the same has started on its next outward movement. The first bar 54 can now be removed, as whatever pull is exerted

by the cloth will now be taken up by the 65 bar 54 at the right; or two rods may be used at each end, each time removing the under one. In this way a succession of layers of cloth can be put down in folds until the desired number is reached. 70

By means of the pivot bolt 8' it will be observed that the cloth rack 8 is reversible, that is, it can be swung around until the rolls 18 and 19 are supported above the rear edge of the truck 5. In this position the 75 cloth can be laid when the truck passes to the left, by causing it to pass under the truck, arranging the layers so that it will pass outward over both the rollers 18 and 19, as shown in dotted lines on Fig. 5. 80

Figs. 13 and 14 are views of a cloth measuring device which comprises a pivotal supporting arm 55, attached to the rack 8, and bearing a roller 56. This roller rests on the surface of the cloth passing over the 85 roller 14, and is rotated as the cloth is paid out. A suitable registering device is connected to the spindle of the roller or disk 56, to indicate the number of revolutions. 90

Fig. 15 is a view of a modification of a 95 cloth laying truck, the body of which is indicated at 57. This truck is provided with an inclined pivoted support 58, which has longitudinally slotted arms 59 connected to its sides to support the same in adjusted position. Suitable screws 60, carried in the sides of the truck 57, engage the slots in the arms 59, and serve as fastening devices therefor. 61 is a pile of cloth laid in folds on the truck 57, and this cloth is paid out 100 by being passed over the inclined support 58, out under the tension device 21, and through the guide frame 31. This guide frame 31 is adjustable the same as the guide frame carried by the truck 5. As the pile of cloth 61 is 105 lessened, the support 58 is of course lowered to keep its upper edge approximately level with the top of the pile. While the cloth is being paid out, the support 58 keeps the pile from being tumbled or pulled over. 110

The cloth in the pile 61 shown on Fig. 15 is shown as folded lengthwise, the same as the cloth in the roll 13, but it is obvious that I may use this apparatus to lay a single ply 115 of cloth as well; and the same is true of the cloth laying apparatus shown on Fig. 2.

It will be understood that the form of truck shown in Fig. 15 is especially useful in handling cloth which is piled in folds or layers in the manner shown in Fig. 11, 120 for the purpose of cutting cloth so filed into the requisite lengths to be worked into the form of garments. —

I wish to reserve to myself the right to make such small changes in the shape, size 125 and arrangement of the parts as fairly fall within the scope and nature of my invention.

Having thus described my invention, I claim as new and desire to secure by Letters Patent:

1. A cutter attachment for a cloth laying machine comprising a relatively stationary member having a plurality of recesses in its upper face, a longitudinal slot therethrough and a relatively movable member consisting of a bar having a plate yieldably attached to the bottom thereof, said bar and said plate having slots therethrough to register with the slot in the stationary member, said plate having holes therethrough to register with the recesses in the stationary member, and a plurality of pointed projections to extend from the lower surface of said bar through the holes in the plate into the recesses in the lower member, when the cloth is laid on the upper face of the relatively stationary member, and the relatively movable member is brought into engagement therewith, so that the pointed projections on the relatively movable member will engage the cloth and hold the same against movement when the cutter knife is moved through the guide slots to sever the cloth.

2. In a cloth laying machine, a tensioning attachment consisting of a bar adapted to rest upon the top surface of the cloth that is being laid, a pair of sliding shoes pivoted to the ends of the bar adjacent the forward edge thereof, guide blocks receiving said sliding shoes, said sliding shoes having slots therein, and fastening bolts passing through said slots and engaging said guide blocks to hold said sliding shoes and the forward edge of said bar in adjusted position.

3. Cloth laying apparatus comprising a stand and uprights arranged in two pairs on opposite sides of said stand, said pairs of uprights being spaced apart, a movable truck having a guide frame projecting from one end, said frame being adapted to move between said uprights from one pair to another, transverse bars engaging the sides of said uprights around which bars the cloth is adapted to be folded, said bars being removable to permit any number of folds of cloth to be laid down between the uprights by the cloth laying machine as may be desired, and a vertical rack bar associated with each member of one pair of said uprights, said rack bar having notches in its face, in which one of the transverse rods is received.

4. Cloth laying apparatus comprising a movable truck having an inclined pivoted support mounted on the top thereof, and means for raising and lowering the upper edge of said inclined pivoted support, said support serving as a guide for a folded pile of cloth, to keep the same from being pulled over or tumbled as the cloth is paid out.

5. A cloth laying device comprising a

smooth plate over which the cloth passes, and a tension device comprising a transverse bar supported above said plate and adapted to rest upon the cloth, said bar having a facing of fabric to engage the upper surface of the cloth and tension the same as the cloth is paid out.

6. In a cloth laying device, a tensioning attachment comprising a smooth bar transversely arranged with respect to the cloth that is to be laid, said bar being located to have the cloth pass over its upper surface, a transverse bar supported above said smooth bar and having a facing of fabric on its lower side to engage the top surface of the cloth, and means for supporting said transverse bar in adjusted position.

7. In a cloth laying device, a tensioning attachment comprising a smooth bar located in position to have the cloth pass over its upper surface, a bar resting upon the upper surface of the cloth and having a facing of fabric on its lower side to have frictional engagement with the cloth, and means for raising and lowering the forward edge of said bar so as to tilt said bar to a certain extent around its rear edge, and cause a greater or smaller width of the fabric facing on the under side of said bar to be brought into frictional contact with the upper surface of the cloth that is being laid.

8. In a cloth laying device, the combination of a truck having a frame pivotally connected thereto, said frame comprising transverse guide rods, a plate carried by said truck adjacent the pivoted end of the frame, said plate having a curved slot therein, and means carried by the said frame and located within said slot to engage the plate and hold the frame in adjusted position.

9. Cloth laying apparatus comprising a movable truck having an inclined support mounted on the top thereof and a pair of links pivotally connected to the support and having pin and slot connection with said truck to enable said support to be adjusted in raised or lowered position, said support serving as a guide for a folded pile of cloth, to keep the same from being pulled or tumbled over as the cloth is paid out.

10. A cutter attachment for a cloth laying machine, comprising a relatively stationary member having recesses in its upper face and a longitudinal slot therethrough and a relatively movable member having a corresponding slot therethrough, and a plurality of pointed projections extending from the lower face of the relatively movable member to enter said recesses, said pointed projections engaging a piece of cloth to hold the same against movement when a cutter knife is moved through the slots to sever the cloth.

11. A cutter attachment for a cloth laying machine, comprising a relatively stationary

member having a plurality of recesses in its upper face and a longitudinal slot therethrough, a second member having a coinciding slot therethrough, and resilient means for pressing the second member toward the first member to engage and hold a piece of cloth between the said members when the said cloth is to be cut.

In testimony whereof I have signed my name to this specification in the presence of 10 two subscribing witnesses.

MOSES ISAACS.
